UNITED STATES PATENT OFFICE.

PAUL NICHOLAY, OF DETROIT, MICHIGAN, ASSIGNOR TO DECELECO, INC., OF DETROIT, MICHIGAN.

MEANS FOR SUPPORTING DETACHABLE ELECTRIC BARRIERS.

Application filed February 10, 1926. Serial No. 87,436.

This invention relates to means for supporting detachable barriers between high tension conductors and apparatus in electric power plants and the like, and has for its 5 principal object the provision of anchor strips in the walls of the building constructed and arranged to readily support detachable electric barriers at any time after the building has been erected.

10 In my companion application, Serial No. 684,753, I have disclosed preferred constructions of detachable electric barriers for use between high tension conductors and electrical apparatus, but in practice I have 15 found that the usual wall construction of electric power houses, substations, etc. are not arranged to conveniently receive such electric barriers, and it has been found necessary to design special anchor strips to be 20 imbedded in the walls to provide a foundation for the mounting of my improved barriers. The present application discloses such anchor strips, and the preferred means of securing them within the brick and concrete 25 walls usually employed in constructing buildings adapted to house high tension electrical apparatus.

A further object of my invention is the provision of an anchor strip adapted to be 30 secured within a building wall with its inner face substantially flush with the inner face of the wall, and having a groove of sufficient width to receive the rear portions 35 of detachable electric barriers, socket blocks being imbedded within the anchor strips in position to receive the bolts or other securing means utilized for fastening the barriers upon the anchor strips.

A further object of my invention is the 40 construction of a wall for buildings housing high tension electric conductors and apparatus wherein a plurality of grooved anchor strips are secured at predetermined distances with their inner faces substantially flush 45 with the inner faces of the wall, whereby detachable electric barriers may be conveniently fastened to and removed from the wall whenever desired.

Other objects and advantages will be apparent from the following description, 50 wherein reference is made to the accompanying drawings illustrating preferred embodiments of my invention and wherein similar

reference numerals designate similar parts throughout the several views.

55

In the drawings:

Fig. 1 is a detail sectional view through one side wall, floor and ceiling of a room in a power house, the wall and ceiling being constructed in accordance with my invention.

60

Fig. 2 is an elevation of the disclosure in Fig. 1, looking from the right of Fig. 1.

70

Fig. 3 is a detail sectional view through a partition wall through which electric conductors are adapted to pass, and provided with means for securing vertical electric barriers on one side of the wall and horizontal electric barriers on the other side of the wall.

65

Fig. 4 is an elevation of the disclosure in Fig. 3, looking from the right of Fig. 3.

75

Fig. 5 is an elevation of the disclosure in Fig. 3, looking from the left of Fig. 3.

80

Fig. 6 is a detail perspective view showing the manner of mounting one of my improved anchor strips in a brick wall, and the manner of mounting a detachable barrier upon the anchor strip.

85

Fig. 7 is a detail vertical section through a detachable barrier, the anchor strip to which it is connected and the wall in which the anchor strip is imbedded.

90

Fig. 8 is a detail cross sectional view, taken substantially on the line 8-8 of Fig. 7.

85

Fig. 9 is a detail perspective view, with parts broken away, showing the manner of mounting a horizontal anchor strip in a brick wall and the manner of mounting a detachable barrier in such anchor strip.

90

Fig. 10 is a detail vertical section through a horizontal anchor strip imbedded in a brick wall and carrying a horizontal barrier, and

95

Fig. 11 is a front elevation of one of the socket members utilized for holding the inner extremities of the bolts used in securing the barriers on the anchor strips.

Referring now to the drawings, the numeral 5 designates the floor of an electric power plant, and the numerals 6 and 7 the side wall and ceiling of a room therein. An electric power plant is shown by way of example because there are located electrical apparatus and conductors adapted to carry high tension loads and, accordingly, detach-

100

105

able barriers are particularly useful therein. It is to be understood, however, that the present invention is also useful in other locations, such as electrical substations, and 5 in fact wherever high tension conductors or apparatus are installed.

In Figs. 1 and 2 a plurality of electric apparatus 8 and bus bars 9 are separated by vertical barriers 10 so as to isolate the several electric members, and also to insulate them against possible arcing. Each barrier is formed of a plurality of demountable sections 11 formed of fire-proof as well as electric insulating materials, and arranged 15 to be detachably secured to a horizontal or vertical portion of the power plant, such as the ceiling 7 or side wall 6. These barriers are fully disclosed and claimed in my companion application, Serial No. 684,753, filed 20 January 7, 1924, and are not specifically claimed in the present application. The barriers are provided with apertures 12 to permit the passage of elongated bolts 13, one extremity of which, as the head, is adapted 25 to be secured within a socket block 14 imbedded or otherwise suitably secured in the anchor strips 15. The socket blocks 14 are preferably arranged substantially as shown in Figs. 6, 8 and 11 with spaced front and 30 rear walls and a keyhole slot 16 arranged in the front wall to permit the ready insertion of the head of the bolt 13 through the larger portion of the slot and the locking of the bolt within the socket block when the bolt 35 is moved into the narrower portion of the slot 16. The socket blocks 14 are preferably imbedded in the anchor strips 15 with their inner faces substantially flush with the bottom wall of the groove 17 formed in the 40 front face of the anchor strip, substantially as shown in Figs. 6 and 7. If desired a plurality of projecting members 18 may extend from the rear face of the socket block 14 so as to firmly fasten the socket blocks 45 within the anchor strips.

The anchor strips 15 are preferably formed of concrete or other moldable material, with a depth substantially equal to the depth of one row of bricks in a brick wall. The sides of the anchor strips may be tapered to facilitate the locking of the strips within a brick or concrete wall, and if desired a plurality of projecting members 19 may have one of their extremities imbedded 55 within the strips 15 with pins 20 passing through apertures in the imbedded ends of the projections 19 serving to more firmly lock the projections within the strips 15. The portions of the projections 19 not imbedded within the strips 15 are adapted to 60 extend into the wall so as to aid in securing the strips 15 within the wall, and with this end in view the free extremities of the projections 19 may be angularly disposed to 65 the central portion of the projections.

The inner faces of the anchor strips 15 are preferably arranged substantially flush with the inner faces of the walls in which the strips are imbedded, and the grooves 17 are preferably arranged substantially centrally between the side edges of the anchor strips 15 with their bottom wall spaced a suitable distance from the inner face of the anchor strips. The anchor strips are preferably molded in suitable lengths with the 70 socket blocks 14 spaced at predetermined intervals upon and lightly secured to one face of the mold during the molding operation, the mold face being then stripped off so as to leave the socket blocks imbedded. 75 In pouring concrete walls, I may do without special anchor strips and provide only a board of substantially the dimensions of the groove desired, and lightly fasten to the board the desired socket blocks at predetermined intervals. The board, accordingly, acts as a form for the groove during the molding of the concrete wall and holds the socket blocks 14 in their desired positions with their slotted faces substantially flush 80 with the bottom wall of the grooves. Then after the wall has set, the boards may be removed from the strips, leaving the socket blocks 14 imbedded at their desired 85 positions.

In constructing brick walls of a power house, etc. in accordance with my invention the anchor strips 15 are positioned at spaced intervals vertically and horizontally, as required, the bricks being laid around the 100 strips 15. The projections 19 extending from the rear face of the anchor strips as well as the tapered side walls of the anchor strips serve to securely fasten the strips 15 within the wall.

The spacing of the anchor strips 15 within the wall may be in accordance with the desired location of electrical apparatus, conductors, etc., or they may be spaced at regular intervals to permit ready change of location of electrical apparatus, conductors, etc. as desired after the building is constructed.

When it is desired to position the barrier sections 11 upon the anchor strips 15 the 115 elongated bolts 13 are positioned in the apertures 12 of the barriers and the heads of the bolts passed through the slotted socket blocks 14. The rear portions of the barrier sections are then positioned within the 120 grooves of the anchor strips, and nuts 13^a threaded upon the bolts and turned until the barriers are secured in place. The sides of the grooves 17 serve to support the sides of the barrier sections.

When horizontal electric barriers 11^a are utilized, it is preferred to have the grooves 17^a in the anchor strips 15 of greater width than the grooves 17 used for receiving the vertical barrier sections 11, and the rear por- 130

tions of the horizontal barrier sections 11^a are provided with a reinforcing portion 11^b (note Figs. 9 and 10) adapted to brace the barrier sections while they engage the anchor strips 15. The widened rear portions of the horizontal barrier sections 11^a are adapted to fit within the widened grooves 17^a of the anchor strips, and the bolts 12 for securing these barrier sections in position 10 pass through the upper portion of the barrier sections substantially as shown in Fig. 10.

While it will be apparent that the illustrated embodiments of my invention herein disclosed are well calculated to adequately fulfill the objects and advantages primarily stated, it is to be understood that the invention is susceptible to variation, modification and change within the spirit and scope of 20 the subjoined claims.

Having described my invention, I claim—

1. An anchor strip for supporting detachable electric barriers comprising sections of moldable material adapted to be imbedded within a building wall each section having a groove in its front face of substantially the width of the barriers to be used therewith, there being socket blocks secured within the anchor strip with their front 25 faces substantially flush with the bottom wall of the groove, and projections adapted to aid in securing the anchor strips within the building wall having one of their ends imbedded within the anchor strip.
2. A supporting wall for electric barriers comprising a wall having a plurality of spaced vertical and horizontal anchor strips arranged with their front faces substantially flush with the face of the wall and their 30 sides tapered to aid in securing the anchor

strips within the wall, each anchor strip having a longitudinal groove in its front face and a plurality of spaced socket blocks imbedded within the anchor strip with their front faces substantially flush with the bottom wall of the groove. 45

3. An anchor strip for supporting detachable electric barriers comprising sections of moldable material adapted to be imbedded within a building wall, each section having a groove in its front face of substantially the width of the barriers to be used therewith, there being socket blocks secured within the anchor strip with their front faces substantially flush with the bottom wall of the groove, and projections adapted to aid in securing the socket blocks within the anchor strip having one of their ends imbedded within the anchor strip. 50

4. An anchor strip for supporting detachable electric barriers comprising sections of moldable material adapted to be imbedded within a building wall, each section having a groove in its front face of substantially the width of the barriers to be used therewith, there being socket blocks secured within the anchor strip with their front faces substantially flush with the bottom wall of the groove, projections adapted to aid in securing the anchor strips within the building wall having one of their ends imbedded within the anchor strip and projections adapted to aid in securing the socket blocks within the anchor strip having one of their ends imbedded within the anchor strip. 55

In witness whereof I hereunto set my hand.

PAUL NICHOLAY.
